Primary Examiner — Jack Reickel*Assistant Examiner* — Keith J Wilson(74) *Attorney, Agent, or Firm* — Snell & Wilmer L.L.P.(57) **CLAIM**

The ornamental design for a showerhead vacuum transport, as shown and described.

DESCRIPTION

FIG. 1 is a top perspective view of a showerhead vacuum transport showing my new design;
 FIG. 2 is a bottom perspective view thereof;
 FIG. 3 is a top plan view thereof;
 FIG. 4 is a bottom plan view thereof;
 FIG. 5 is a front elevational view thereof;
 FIG. 6 is a rear elevational view thereof;
 FIG. 7 is a right side elevational view thereof; and,
 FIG. 8 is a left side elevational view thereof.
